UNITED STATES PATENT OFFICE.

DAVID LEY RAITT, OF LONDON, ENGLAND.

LAMP SHADE AND OTHER TRANSLUCENT SCREEN.

Application filed April 16, 1925, Serial No. 23,636, and in Great Britain April 30, 1924.

This invention relates to translucent screens and lamp shades for gas or electric light of the type comprising a framework adapted to carry in the sides thereof panels or plates of glass, cardboard, or other material.

The object of the invention is to provide an improved construction of frame which will be rigid in construction, neat in appearance and has means whereby the panels or the like can be readily interchanged.

In the preferred form of the invention, the frame is polygonal in form and may be either an open or closed polygon, and the panels of glass or other translucent material carry advertising matter which becomes illuminated by the lamp.

According to the invention the frame comprises upper and lower rigid polygonal members having rectilinear faces and spacing rods holding them fixedly apart. The rectilinear edges of the upper and lower members are provided with lips, lugs, or other projections against which removable panels may abut and on the spacing rods are mounted hinged flaps adapted to fold over and retain the panels against said abutments. Preferably the upper and lower polygonal members are formed of angle metal of which the vertical web provides the abutment and the horizontal web means to prevent the panels from sliding up or down and the flaps are controlled by spring means tending to maintain them in the closed position.

The invention is illustrated in the accompanying drawing in which—

Fig. 1 illustrates a lamp shade of the lantern type, and Fig. 2 a translucent shade comprising only three vertical panels.

Referring now to the drawing, the device according to Fig. 1 comprises upper and lower rigid polygonal members 1, 2 formed of angle metal comprising horizontal webs 1^a, 2^a and vertical webs 1^b, 2^b. The upper part of the lamp is completed by a dome-shaped plate 3 having a central hole for the mounting of a lamp socket 4, and the lower part may be open or closed by a simple plate. The members 1, 2 are held apart by means of circular rods 5 on each of which are mounted two hinged flaps such as those indicated at 6^a, 6^b. The transparent panel 7 is adapted to be held between upper and lower webs 1^a, 2^a and against the upper and lower vertical webs 1^b, 2^b by

means of the hinged flaps which fold over and retain the panel in its proper position as will be readily understood. In the drawing, the flap marked 6^b is illustrated as being open in order to allow the corresponding panel 7 to be withdrawn. Preferably two flaps 6^a, 6^b on one pillar are both urged into the closing position by means of a single spiral spring such as that illustrated at 8.

It is to be understood that the invention is not limited to the form above described comprising a lantern-like hanging shade. On the other hand a screen-like shade is illustrated in Fig. 2 which is also constructed according to the present invention, the said shade comprising a stand supporting a translucent screen of three plane panels set at angles to each other, the panels being held by similar means to those illustrated with regard to Fig. 1.

Clearly the device illustrated in Fig. 2 may have a reflecting back if desired without departing from the spirit of the invention, and it is therefore to be understood that the upper and lower frameworks are not restricted to the shape of a closed polygon, but that the invention covers either an open polygon or the arrangement of panels in line in a single plane.

In a modification the invention may be applied to a sign illuminated from within having a straight front comprising a series of panels arranged all in one plane and susceptible of replacement and exchange. In such a sign the angle bars will preferably be used for the upper and lower framing and vertical rods provided at intervals along the length of the bars with double hinged flaps for the replacement and exchange of the panels in the manner described.

I claim:

1. Frame for translucent screen comprising parallel rigid polygonal members, abutment members thereon, transverse spacing rods between said parallel members, retaining flaps hinged about said rods for movement in a plane at right angles thereto, and springs permanently urging said flaps in retaining position.

2. Frame for translucent screen comprising parallel rigid polygonal members, abutment members thereon, transverse spacing rods between said parallel members, retaining flaps hinged about said rods for movement in a plane at right angles thereto, and

2
springs permanently coiled round said rods to urge said flaps in closing position.

3. A frame for holding a panel including upper and lower members against which the panel is adapted to rest, and opposing retaining members adapted for pivotal movement with respect to the frame to overlie the edges of the panel, and springs serving to operate the retaining members toward the panel and for exerting a panel holding pressure on said members, the panel as supported by the upper and lower members serving as a limit for the operative movement of the retaining members.

15 4. A frame for holding a removable panel, consisting of relatively fixed upper and lower frame bars to receive the panel and side bars mounted for swinging movement with respect to the upper and lower frame bars to permit said side bars to be moved into a position to bear upon the panel or to a position to free the corresponding edges of the panel, and springs serving to operate the retaining members toward the

panel and for exerting a panel holding pressure on said members, the panel as supported by the upper and lower members serving as a limit for the operative movement of the retaining members. 25

5. A panel receiving frame comprising upper and lower relatively fixed panel receiving frame bars, rods connecting said frame bars and arranged beyond the edges of the cooperating panel, and flaps mounted for swinging movement on said rods and extending throughout the length thereof, the free edges of the flaps being adapted to overlie the adjacent edges of the panel when the flaps are in closing positions, and means to normally urge the flaps toward closing position, said means exerting a holding pressure on the flaps following the movement of the flaps to closing position, the panel as supported by the upper and lower members serving as a limit for the operative movement of the retaining members. 30 35 40 45

In testimony whereof I affix my signature.

DAVID LEY RAITT.
